UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC CANDLE AND THE LIKE.

1,252,587.

Specification of Letters Patent.

Patented Jan. 8, 1918.

Application filed November 13, 1915. Serial No. 61,211.

To all whom it may concern:

Be it known that I, CHARLES J. KLEIN, a citizen of the United States, residing at Milwaukee, in the county of Milwaukee and State of Wisconsin, have invented new and useful Improvements in Electric Candles and the like, of which the following is a full, clear, concise, and exact description, reference being had to the accompanying drawing, forming a part of this specification.

This invention relates to improvements in electric candles and the like.

The invention has among its objects to provide a simplified and comparatively inexpensive electric fitting for candles and the like, such fitting to be either of the switch or switchless type.

A further object is to provide an electric fitting of the aforesaid character which may be readily and conveniently attached to a fixture and wired for use.

A still further object is to provide a simplified and neat appearing candle unit including a candle shell and support therefor.

Other objects and advantages of the invention will hereinafter appear.

The accompanying drawing illustrates one embodiment of the invention and the same will now be described, it being understood that the invention is susceptible of modifications falling within the scope of the appended claims.

In the drawing,

Figure 1 is a side elevation of a complete candle unit of the switch type;

Fig. 2 is a similar view but with the candle shell sectioned to disclose the electric fitting therein,

Fig. 3 is a top plan view of Fig. 1,

Fig. 4 is a view showing the candle shell sectioned on line 4—4, Fig. 2 and showing in plan the switch carrying base part directly above said line;

Fig. 5 is a sectional view taken on line 5—5, Fig. 2, and showing the opposite face of the base part shown in Fig. 4.

Fig. 6 is a sectional view taken on line 6—6, Fig. 4.

First considering the candle unit exteriorly, the same comprises a cylindrical tube 6 fitting at its lower end into a cap 7 having a threaded bushing 8 for attachment thereof to the usual fixture nipple. The tube is of suitable length to represent a candle and both the shell and cap are designed to

have a candle finish whereby the unit may be mounted in the usual cup for candle effect. Any suitable materials may be employed for the shell and cap. The shell, however, is preferably formed of resilient material whereby it may be sprung into locking engagement with catches 9 on the cap and also preferably formed of insulating material whereby the use of special interior insulation therefor will be rendered unnecessary. By means of the snap catches 9 the candle shell may be readily and firmly locked in the cap while said parts may be readily released and separated for access to the enclosed fitting.

Next considering the electric fitting, the same in brief, comprises a single set of lamp socket parts and means of any exceedingly simple character to adapt such parts to a candle or the like. The fitting includes a base 10 provided with line terminals 11 and 12 in the form of screw binding posts (Figs. 2, 4 and 5), terminal extensions 13, 14 and 15 and a screw shell 16 electrically connected with and supported by the terminal extensions 13 and 14. The terminal extensions 13 and 14 support the screw shell 16 adjacent to the open end of the candle shell while the extension 15 has a button extremity 17 forming a center contact for said screw shell. The fitting, as illustrated, is of the switch type, being equipped with a switch mechanism arranged within the base 10 and provided with opposed push buttons 18 and 19 projecting through the candle shell and at diametrically opposite points. However, as will be apparent, the arrangement of the parts just described is equally well adapted to a switchless fitting.

More specifically describing the fitting, the base 10 is so constructed as to rest upon an internal shoulder 20 of the cap and to be clamped against said shoulder by the extremity of the candle shell. The base is divided horizontally into two sections 10^a and 10^b to receive the switch mechanism therebetween and, as illustrated in Fig. 4, the switch mechanism is of the so-called "hill and valley" type. Briefly described, this switch mechanism, which is fixed to the under side of the base section 10^a, includes a reciprocable "hill and valley" cam member 21 acting upon an oscillating contactor to make and break circuit between contacts 23 and 24 respectively connected with the 105 110

binding post 11 and the center terminal extension 15. As will be observed from Figs. 4, 5 and 6, the contact 23 is secured through the base section 10^a to a plate 25 carrying the post 11 while the contact 24 is connected through the base to the angular extremity 26 of the center terminal extension 15. Thus a circuit is completed from binding post 11 through the switch to the center terminal 12 while the return circuit is through the screw shell 16 by terminal extensions 13 and 14 to binding post 12. Referring to Figs. 5 and 6, the binding post 12 is carried by an arc-shaped plate 27 on the upper side of the base while the extremities of the terminal extensions 13 and 14 are bent to underlie said plate and holding screws 28 and 29 are passed through the former and threaded into the latter. These screws, as will be observed from Fig. 2, also extend through both sections of the base and thereby further serve to secure said base sections together. As will be observed from Figs. 5 and 6, the plate 27 and extremities of terminal extensions 13 and 14 overlie other conducting parts and for separation thereof an insulating disk 30 is provided. An insulating disk 31 is also inserted in the screw shell to secure the center terminal in spaced relation with said shell and a dished disk 32 is attached to the base 10 to provide a lining for the cap 7. Further insulation of the fitting is unnecessary where the candle shell is of insulating material but the fitting may be readily insulated through its length if desired by a simple fiber sleeve.

Thus is provided a simple, unitary and inexpensive fitting which is applicable to practically any candle fixture and susceptible of quick and easy installation and a complete candle having the added advantage of a simple, neat and inexpensive candle shell and support combined with the fitting into unitary form.

45 What I claim as new and desire to secure by Letters Patent is:

1. The combination with a candle shell, of a unitary lamp socket fitting therefor, comprising a supporting base provided with a plurality of terminals, a screw shell terminal, a center terminal and separate conducting brackets supporting said screw shell and center terminals upon and in a spaced relation with said base for rendering said fitting coextensive with said shell, each of said brackets affording a direct electrical connection between the terminal supported thereby and one of said terminals of said base.

60 2. The combination with a candle shell, of a supporting cap fitting the lower end of said shell and a unitary and coextensive

lamp socket fitting for said shell including a combined supporting and terminal base resting within and supported by said cap, 65 lamp engaging terminals and spacing members between said base and terminals to support the latter adjacent to the open end of said candle shell, said candle shell being lockable within said cap and serving when 70 so locked to secure said fitting base within said cap, said fitting base being freed for removal from said cap upon release and removal of said candle shell.

3. The combination with a candle shell, 75 of a supporting cap fitting the lower end of said shell, said shell and cap having means to releasably secure the same together and a unitary lamp socket fitting for said shell comprising a combined terminal base and 80 switch resting within and supported by said cap, lamp terminals and conducting and spacing connections between said lamp terminals and said combined terminal base and switch to support the former adjacent to the 85 open end of said shell.

4. As an article of manufacture, a unitary lamp socket fitting for candles and the like, comprising a supporting base provided with a plurality of terminals, a screw shell terminal, a center terminal and separate conducting brackets supporting said screw shell and center terminals upon and in a spaced relation with said base for given external longitudinal dimensions of the fitting, each 90 of said brackets affording a direct electrical connection between the terminal supported thereby and one of said terminals of said base.

5. As an article of manufacture, a unitary lamp socket fitting for candles and the like, comprising a terminal base, a screw shell, a pair of brackets, one a terminal extension from said base, for supporting said shell upon and in a spaced relation with 105 said base, a center terminal within said shell, a terminal extension from said base carrying and independently supporting said center terminal and means centering said terminal within said shell.

6. As an article of manufacture, a unitary lamp socket fitting for candles and the like, comprising a transversely divided terminal base, a switch mechanism mounted between the parts of said base, a plurality of terminal extensions fixed to said base and a screw shell and center terminal carried by said terminal extensions and spaced thereby from said base and the inclosed switch mechanism.

In witness whereof, I have hereunto subscribed my name.

CHARLES J. KLEIN.
